UNITED STATES PATENT OFFICE

HENRI G. LEVY, OF SAN FRANCISCO, CALIFORNIA

HAIR DRIER

Application filed July 8, 1929. Serial No. 376,508.

This invention relates generally to the construction of apparatus for drying hair, and particularly driers of the type utilizing an electrical source of heat in conjunction with a motor driven fan or blower.

It is a general object of this invention to devise improved apparatus of the above character which will make possible effective and thorough drying of the hair in a minimum amount of time, and with utmost comfort to the user.

It is a further object of this invention to devise novel and improved diffusing means for use in conjunction with a hair drier of the above character, whereby currents of air are applied to the user's head in a manner which will produce most efficient and uniform drying.

Further objects of the invention will appear from the following description in which I have set forth the preferred embodiment of my invention. It is to be understood that the appended claims are to be accorded a range of equivalents consistent with the state of the prior art.

Referring to the drawings:

Figure 1 is a side elevational view illustrating an apparatus incorporating my invention.

Fig. 2 is a detail view looking toward the open end of the diffuser shown in Fig. 1.

Fig. 3 is a cross sectional detail of the diffuser taken along the line 3—3 of Fig. 1.

Fig. 4 is a cross sectional view taken along the line 4—4 of Fig. 2.

Fig. 5 is a perspective detail partly in cross section, illustrating the arrangement of louvres for deflecting air currents.

Electrical hair driers of the prior art have commonly utilized an electrical fan or blower connected to a discharge conduit, in combination with electrical or equivalent means for supplying heat. Such apparatus discharges a relatively concentrated stream of heated air which is manually directed upon different portions of the head of the user. The use of concentrated blasts of hot air in this manner is wasteful and inefficient, it requires continual manipulation by an operator, and the drying process is frequently un-

comfortable to the user. As disclosed in my Patent No. 1,744,586, granted January 21, 1930, I have found that it is desirable to employ a diffuser connected to the conduit from the fan or blower, for distributing the heated drying air to substantially all parts of the hair simultaneously. The present invention is in some respects an improvement of that disclosed in said Patent No. 1,744,586 particularly with respect to the manner in which the air currents are deflected and distributed within the diffuser to secure most uniform and efficient drying.

Referring to the drawings, I have disclosed my apparatus as comprising a fan or blower 11, driven by means of a suitable electrical motor 12. The blower and its driving motor are suitably supported by a standard 13, which is preferably vertically adjustable. Generally standard 13 is provided with an upper fork 14, pivotally connected to the motor 12, whereby the motor and the blower can be bodily swung in a vertical plane about the pivotal axis of the motor and blower shaft. Air is discharged from blower 11 thru a suitable conduit 16. For heating the air discharged by conduit 16, suitable electrical heating elements are provided, these elements being positioned either within the conduit 16 or within the housing of blower 11, so that the currents of air must come into contact with the same. The construction and arrangement of such electrical heating elements is well known in the art, and they need not be described in detail. It is sufficient to state that the heating elements should be controllable by a suitable switch, so that varying degrees of heat can be supplied.

Connected to the discharge end of conduit 16, I provide what can be termed a diffuser, or diffusing member. This member is preferably bell-shaped, and when in normal operating position its large open end is faced in a general downward direction. It is sufficiently large to accommodate the head of the user in such a manner that only the face and lower side portions of the head are exposed. The smaller end portion 18 of the diffuser is connected to conduit 16 by means of a curved conduit section 19. The connection between

conduit section 19 and conduit 16, is preferably arranged in such a manner as to permit the diffuser to be swung back to an out of the way position, as shown in dotted lines in Fig. 1, and also to permit ready removal of the diffuser together with conduit section 19. For this purpose a hook 21 is shown secured to the upper edge of conduit section 19, and this hook is adapted to engage a U-shaped member 22 secured to the upper edge of conduit 16. To engage hook 21 with member 22, the diffuser must be positioned somewhat as shown in dotted lines in Fig. 1, after which the diffuser can be swung forwardly to operating position.

From the above, it is evident that when the diffuser 17 is in normal operating position, it can be said to have two side wall portions 23, a front wall portion 24, and a back wall portion 26, corresponding respectively to the sides, front and back of the head of the user. The lower edge of back wall portion 26 is preferably struck or bent out to form a flange portion 27, which provides comfortable contact with the back of the neck.

If the above described diffuser were employed without additional means for properly deflecting and distributing the air within the same, a concentrated stream of air would be discharged from conduit section 19, directly upon top of the head, while the sides of the head would not be in the direct path of air currents, and thus a non-uniform drying effect would result. As a novel means for securing proper distribution of air currents, I have shown vanes or louvres 31 and 32 disposed adjacent the small end portion 18 of the diffuser 17, so as to deflect and distribute air currents being discharged downwardly toward the large end of the diffuser. Louvres 31 are preferably offset from the centered line 33 of diffuser 17, and extend in substantially the same general direction as the corresponding side wall portions 23. They are also positioned at an angle to the center line 33 so as to deflect air currents striking the same towards the corresponding side wall portions 23, as shown in Fig. 3. Louvres 32 are spaced and inclined similarly with respect to center line 33, but in a direction opposite from the inclination of louvres 31.

To facilitate manufacture, louvres 31 and 32 can be in the form of flat metal strips, having their ends welded or otherwise suitably secured to a metal ring 34. Ring 34 can be frictionally retained within an annular U-shaped portion 36 formed integral with the walls of diffuser 17. Portion 36 is adapted to telescopically interfit an annular socket portion 37 formed upon the adjacent end of conduit section 19, and a plurality of set screws 38 threaded thru portion 37, serve as convenient means for forming a detachable

interlocking engagement between conduit section 19 and diffuser 17.

The effect of louvres 31 and 32 is as follows: The center portion of the air stream issuing from conduit section 19, is free to pass between louvres 31 and 32 without deflection, and is therefore impressed upon the top portion of the head of the user. However one side of the air stream is deflected by louvres 31 and directed downwardly along the corresponding side wall portion 23, and along the side of the head of the user. Correspondingly air currents from the opposite side of conduit section 19 are deflected by louvres 32 so as to direct air currents downwardly along the opposite side wall portion 23. Thus the air currents within the diffuser are distributed uniformly to both the side and top portions of the head.

With the arrangement of louvres 31 and 32 described above, I have found that an unpleasant draught of air may be discharged from the diffuser across both sides of the face from the side wall portions 23. I have found that this can be avoided, and the drying effect along the sides of the head and near the temples can be made more effective, by utilizing flaps or deflectors 41. These flaps are preferably made of resilient material, such as vulcanized rubber, and are each suitably secured to the lower edge of the corresponding side wall portions 23. As an example of suitable securing means, I have shown each flap provided with an integral enlarged edge portion 42, which is retained between a suitable clamping strip 43 and the lower edge of the diffuser. These deflecting strips are preferably inclined inwardly as is apparent from Fig. 3. The air streams which pass downwardly along the sides of the diffuser, strike strips 41 and are thereby deflected inwardly against the sides of the user's head.

With the connection shown between the conduit section 19 and diffuser 17, it has been found that too great a volume of air tends to be discharged forwardly down along the front wall portion 24, and across the user's forehead. Referring to Fig. 4, I offset this tendency by the use of additional louvres 46 which preferably extend substantially at right angles to louvres 31. Louvres 46 are both inclined in the same direction, so as to tend to distribute an adequate amount of air down along the back wall 26, thus preventing too large a quantity of air being discharged from the front of the diffuser. Louvres 46 can also be in the form of flat metal strips positioned adjacent louvres 31 and 32, and having their ends suitably secured to the adjacent end portion of conduit section 19.

The operation of my complete apparatus will be apparent from the above description. Generally the user is seated below the diffuser 17, and the diffuser is lowered over the

user's head. The blower, and heating element with hot air are then put in operation to deliver air currents to the diffuser. The diffuser distributes air to all parts of the head to secure uniform and quick drying action. If desired the diffuser can be swung back to the position as shown in dotted lines in Fig. 1, or it can be removed and other diffusers or other forms of air discharge nozzles can be substituted.

10 I claim:

1. In a hair drier, a bell shaped member adapted to accommodate the head of a user with the large open end thereof directed downwardly, a conduit connected to the smaller end of said member, means for causing a flow of air thru the conduit into said member, said member having front, side, and back wall portions corresponding generally to the front, sides, and back of the head of a user, and air deflecting vanes disposed near the small end of said member, said vanes extending in the same general direction as the side walls and being arranged at different deflecting angles to deflect air currents away from the center of said member towards both side wall portions.

2. In a hair drier, a bell shaped member adapted to accommodate the head of a user with the large open end thereof directed downwardly, a conduit connected to the smaller end of said member, means for causing a flow of air thru the conduit into said member, said member having front, side, and back wall portions corresponding generally to the front, sides, and back of the head of a user, and air deflecting louvres disposed near the discharge end of the conduit, said louvres being set at opposite angles with respect to the center line of the conduit to deflect air currents away from the center of said member towards both side wall portions, said louvres extending in the same general direction as the side wall portions of said member.

3. In a hair drier, a bell shaped member adapted to accommodate the head of a user, means for delivering a stream of air into said member, a plurality of vanes for deflecting the stream of air toward the sides of said member and another vane for directing a portion of said stream downwardly toward the neck of the user.

4. In a hair drier, a bell shaped member adapted to accommodate the head of a user, means for delivering a stream of air into said member, a plurality of vanes for deflecting a portion of the stream of air toward the sides of said member without affecting the direction of another portion of the stream, and another vane for directing part of the stream downwardly toward the neck of the user.

In testimony whereof, I have hereunto set my hand.

15 HENRI G. LEVY.
